CIGARETTE DISPENSING CONTAINER

Edith B. Duell and Charles H. Duell, Detroit,
Mich.; said Charles H. Duell assignor to said
Edith B. Duell

Application June 28, 1946, Serial No. 680,018.

1 Claim. (Cl. 206—41.2)

1

This invention relates to improvements in the construction and operation of cigarette cases or containers of the dispensing type and has for its principal object to provide a new and improved container particularly adapted for holding a supply of cigarettes and so constructed and arranged that the cigarettes may be dispensed from the interior of the container one at a time by tilting the container and sliding the cover thereof to an opened position.

Another object is to disclose means for the attainment of this dispensing action which will permit of great flexibility in the outward design of the cigarette case, and in this connection it is a further object of the invention to illustrate the manner in which the dispensing means may be incorporated in a few representative types of cases.

Another important object of the present invention is to provide a cigarette case having dispensing features associated with each of its ends in order that the user may dispense a cigarette from the case regardless of which of its ends he happens to be holding.

A further object is to insure positive dispensing action and to prevent damage to the cigarettes, either by the action of the dispensing means or otherwise, by insuring the proper positioning of cigarettes within the case at all times, and as a part of this object it is further desired to disclose novel means to provide for such correct positioning of the cigarettes.

The above and other objects of the invention, such as to provide a cigarette dispensing container of neat and attractive appearance, extreme simplicity and capable of being constructed in quantity production of plastics, glass, wood, metal or any other suitable or desired material at a comparatively low cost will appear more fully from the following detailed description of representative types of cases embodying the invention and illustrated in the accompanying drawings wherein

Fig. 1 is a plan view of a full size cigarette case;

Fig. 2 is a sectional side view taken along the line 2—2 of Fig. 1;

Fig. 3 is a sectional side view similar to that of Fig. 2 except that the cover of the case has been shown in one of its opened positions;

Fig. 4 is a sectional end view taken along the line 4—4 of Fig. 1;

Fig. 5 is a sectional side view showing how the invention may be embodied in a half size case;

Fig. 6 is a perspective view of a modified type of full size case with the cover thereof partially opened;

2

Fig. 7 is a sectional view taken along the line 7—7 of Fig. 6 but with the cover of the case in closed position;

Fig. 8 is a sectional view similar to Fig. 7 but showing the cover of the case opened as in Fig. 6;

Fig. 9 is a sectional view similar to Fig. 7, but showing certain modifications in the construction;

Fig. 10 is a plan view of a different type of case embodying the invention, a portion of the cover of this case being broken away; and

Fig. 11 is a sectional view of this case, being taken along the line 11—11 of Fig. 10.

The type of cigarette case shown in Figs. 1 to 4 of the drawings has been designed to hold a full ordinary package of cigarettes and has therefore been referred to as a full-size case. It has a bottom 11, sides 12 and end portions 13, preferably moulded in one piece of any suitable plastic, though, of course, the material of construction may be varied as desired. Each end of portion 13 extends upwardly in a smooth curve from the bottom to approximately one-half of the side depth of the case. A cover 14 is formed with depending end sections 15 which are curved to correspond to the curvature of the end portions 13 so that continuous smoothly rounded ends are presented when the cover is in closed position. Normal movement of the cover for dispensing is sliding, the cover being provided for this purpose with a groove, formed by turning its side edges 16 downwardly and inwardly to engage a tongue 17 which comprises part of the upper edge of each side 12. The extent of this sliding movement of the cover in either direction is defined and limited by stops 18 consisting of small projections extending inwardly from the sides of the case and positioned so as to engage the depending end sections 15 of the cover. To hold the cover in closed position, a friction latch 42, consisting of a small projection extending downwardly on each of the end sections 15 is provided, these latches engaging a small socket 43 formed in each of the end portions of the case.

In loading the case, the cover is removed by pressing inwardly on the sides of the case to disengage the tongues 17 from the grooves of the cover, this operation being made possible by limiting the extent of engagement between the tongues and grooves to an amount easily within the inherent flexibility of the sides.

A dispensing section or trough is formed adjacent and parallel to each end of the case by providing transverse barriers 19 projecting inwardly from the bottom and spaced from each end portion 13 a distance sufficient to form a

trough which can contain but one cigarette. In height the barriers 19 are each dimensioned so as not to present too great an obstruction to the passage of any cigarette from the main body of the case into the dispensing sections thereof, but at the same time these barriers must project above the bottom surface of the case a sufficient distance so that the space remaining between the top 20 of a barrier and the lower edge 21 of a depending end section of the cover, when the cover is in open position, is less than the normal diameter of a cigarette.

Since the length of a full size case of the type shown is considerably greater than the length of any normal cigarette for which the case could be designed, the case has been divided into two compartments by the provision of a centrally located stationary rib 22 extending inwardly from the bottom which, when the cover is in closed position, lies opposite a second rib 23 formed as part of the cover 14 so that the distance between ribs is less than the average diameter of a cigarette. The second rib 23 moves with the cover so that in either open position of the cover the two ribs lie in staggered relationship and the distance between them increases, as shown in Fig. 3, so that a cigarette may roll freely from one compartment of the case to another.

Assuming that this case has been filled with a supply of cigarettes, the manner in which it operates may be described as follows: If the case is full to its capacity, a cigarette will normally be positioned in each of the dispensing troughs in the manner shown by the cigarettes 40 and 41 adjacent the left and right hand ends of the case, respectively, and if there is less than a full supply in the case, the positioning of a cigarette in the dispensing trough to be uncovered can be insured by tilting that end of the case down so as to cause a cigarette to roll over the barrier 19 and into the dispensing trough. To dispense the cigarette then and taking, for example, the cigarette 41 at the right hand end of the case, it is merely necessary to slide the cover to the left until further movement is prevented by the stops 18, using a slight additional force initially to disengage the friction latch 42 of the cover from the socket 43 on the end portion of the case. With the cover opened, the cigarette 41 can be removed from the dispensing trough in any way convenient to the user of the case. During this removal, no other cigarette but the cigarette 41 being dispensed can pass from the main body of the case into the uncovered dispensing trough because, as previously mentioned, such passage is prevented by the restricted distance between the lower edge 21 of the depending end section of the cover and the top surface 20 of the barrier 19. Likewise if before the cover is opened more than one cigarette were located in the dispensing section of the case, such as were a second cigarette positioned above the cigarette 41 in Fig. 2, this second cigarette would be removed from the dispensing section and pushed back into the main part of the case by the depending end 15 of the cover as the latter is slid back to open position.

Precisely the same dispensing action can be obtained from the other end of the case so that regardless of which end of the case is held away from the hand of the user, a single cigarette can be removed from the case each time the cover is slid back. However, it can readily be appreciated that this dispensing action cannot be

positive in operation unless the cigarettes within the case are at all times positioned in substantial parallelism to the ends or dispensing troughs of the case; and the term "substantial parallelism" is used to denote all positions where the length of the cigarette lies principally cross-wise of the case as distinguished from length-wise thereof. With some of the modified forms of the invention which will be described later in this specification, correct positioning of the cigarettes for satisfactory dispensing action is insured from the over-all dimensioning of the case itself by making the case with a shorter length than width, but in the full size flat type case, this is not possible. The length must be greater than the width and therefore the centrally located stationary rib 22, coupled with the second rib 23 of the cover, is provided to prevent any cigarette from occupying a position length-wise of the case and to maintain all cigarettes in substantial parallelism with the dispensing troughs of the case. If a cigarette could assume a length-wise position, that cigarette could be crushed and destroyed by the opening of the cover or the dispensing action could be jammed by the cigarette being caught between the depending end section 15 of the cover and other cigarettes in the case or squeezed between the lower edge 21 of the end of the cover and the top surface of the barrier 19. Another objectionable feature that would accompany such length-wise positioning of cigarettes is that in this position a cigarette would not be free to roll into the dispensing section and to correct this and dispense a cigarette, the user would have to resort to much jiggling and shaking of the case in order to correct the position of the cigarettes, thereby damaging them and loosening the tobacco in the process.

The function of aligning the cigarettes in substantial parallelism with the dispensing sections of the case is performed by the stationary and movable ribs 22 and 23 in both a preventative and corrective manner, i. e., the ribs 22 and 23 divide the case into two compartments, each of a length sufficiently less than the length of a cigarette so that it will be impossible for any cigarette in either of these compartments to assume a position length-wise thereof; or, since the length of a cigarette is but slightly less than the width of the case, the length of each of these compartments may be said to be less than the width of the case. When the cover of the case is closed, the ribs 22 and 23 lie opposite each other and separate the compartments of the case so that it is impossible for a cigarette to pass between compartments, but when the cover of the case is moved in either direction to one of its opened positions, the rib 23 lies in a staggered relationship to the stationary rib 22 (see Fig. 3), forming an opening between the compartments slightly wider than the diameter of a cigarette and parallel to the dispensing sections so that any cigarette passing from one compartment to the other must necessarily lie in the correct parallel position while passing; and if not in such position, the two ribs will cause that cigarette to move to a parallel position. In other words, these two ribs may be said to prevent such length-wise positioning of the cigarettes as would interfere with the operation of the dispensing means or result in damage to the cigarettes, and to aid in correcting any lesser degree of length-wise positioning.

Fig. 5 illustrates the construction of a case similar in practically all respects to the case shown in Figs. 1 to 4 and previously described,

and because of this similarity only the sectional view of this case in Fig. 5 has been included in the drawings. The principal difference between the two cases lies in the fact that the case of Fig. 5 is smaller, being what may be termed a half-size case in contrast to the full size type. Since, by reason of its size, the length of this case is sufficiently less than the length of a cigarette so that there is no chance for mispositioning of cigarettes within the case, the means 10 just described for dividing the case into compartments are not included.

Otherwise, the two cases are identical, and the construction of the half-size case consists of a one piece container having a bottom 25, sides 26 and end portions 27; a top or cover 28 having depending end sections 23 and grooves 29 slidably engaging tongues 30 on the upper edge of the sides 26; and with sliding movement of the cover limited in both directions by stops 31. Barriers 32 extend inwardly from the bottom 25 to form dispensing troughs adjacent each of the ends of the case and the same considerations as have been previously explained pertain to the dimensioning of these barriers and the relationship between their dimensioning and that of the depending end sections 23 of the cover. A small bead 34 is formed as part of each of the end portions 27 and projects above the upper edge of the end portions 27 so as to contact the lower edge of each end section of the cover and act as latches to hold the cover in closed position. The loading of this case, its operation and the functioning of the dispensing means have all been previously discussed in the description of the full-size case.

The forms of this invention heretofore described and illustrated by Figs. 1 to 5 of the invention are thought to be preferable, mainly because of the fact that these cases incorporate the feature of dispensing a single cigarette at a time from either end of the case. Besides offering a great convenience to the user, this feature also enables the design of the case to be simplified and improved because nothing need be included in the design to enable one to distinguish the dispensing end of the case.

However, in order to more fully develop the invention and to disclose other types of dispensing means so that the invention may be applied to cigarette cases of all types, some additional modifications have been shown in Figs. 6 to 11 of the drawings. The case shown in Figs. 6 to 8, and modified in certain respects in Fig. 9, is provided with a bottom 45, side walls 46, a rear wall 47 and a front wall 48. Each of the side walls is provided along its top edge with a protruding rib or tongue 49, and a cover 50, having a depending flange or groove 51 along each of its side edges, is slidably mounted on the case by the engagement of these tongues and grooves. In this modification of the invention, a dispensing trough or section consists of a semi-cylindrical shaped depression 52 formed in the bottom 45 of the case adjacent the front wall 48 thereof, this depression extending across the entire width of the case and being adapted to contain a single cigarette such as is shown by the cigarette 53 in Fig. 8. The cover 50 has a front wall 54 which depends downwardly and cooperates with the front wall 48 of the case to form a complete closure of the dispensing end of the case when the cover is in closed position as shown in Fig. 7 of the drawings. A more snug closure is obtained and movement of the cover is limited to

one direction if the top edge 55 of the front wall 48 of the case and the lower edge 56 of the front wall of the cover are tapered or chamfered in the manner depicted in the cross-sectional views of Figs. 7 to 9.

Adjacent the rear edge of the cover 50, a pair of small indentations or inwardly projecting beads 57 and 58 are provided, the bead 58 engaging the upper edge of the rear wall 47 of the case and serving as a friction latch to hold the cover in closed position, while the bead 57 serves as a stop to limit the sliding opening movement of the cover to the position shown in Fig. 8 of the drawings where the cover is shown opened 15 sufficiently to permit the removal or dispensing of a single cigarette 53. In other words, this opening movement of the cover, as was the case with the previously described embodiments of the invention, is merely sufficient to expose the 20 dispensing section of the case, and the depending front wall 45 of the cover extends downwardly a sufficient distance so that when in open position the distance between the lower edge 56 of the wall 45 and the bottom surface 45 of the case is less than the normal diameter of a cigarette, thereby effectively closing off the dispensing section of the case from the main body thereof when the cover is opened and causing any cigarettes to be removed from the dispensing end of the case except the one contained in the dispensing trough.

Consequently, the dispensing action of this form of the invention is the same in principle as with previously described forms. However, 25 in defining the dispensing section by the depression 52 instead of by the barrier 19, it obviously becomes somewhat easier to move a cigarette to dispensing position in this type of case than in the other.

Being a full size type of case, parallel positioning means is included for best operation and takes the form of a transverse stationary rib or barrier 59, formed in the bottom of the case midway between the front and rear walls thereof, and a depending rib 60 provided on the cover 50 and also extending transversely across the box. Formed in conjunction with the rib 60 is a depression 61 extending partially across the box to act as a finger grip to enable the user to more readily slide the 30 cover in its opening and closing movements. Since this case dispenses from one end only, all movements of cigarettes within the case will be toward the dispensing end and therefore the rib 60 has been located toward the dispensing end of 35 the case so that a communicating passage between the compartments of the case will be presented at all times when the cover is in closed position, and this passage will be blocked by the rib 60 and barrier 59 only when the cover is 40 opened. This may be clearly seen from a comparison of Figs. 7 and 8. Movement of cigarettes to the dispensing section is further facilitated by forming the barrier 59 with a sloping surface 62 in the direction of movement and a vertical or 45 straight surface 63 which acts to restrict movement away from the dispensing section of the case.

This feature is not present in the type of case shown sectionally in Fig. 9 where the stationary 50 rib is shaped as a semi-cylindrical transverse indentation 64 in the bottom of the case which, in combination with a transverse raised portion 65 of the cover, divides the case into compartments. Except for this difference, the case of Fig. 9 is 55 identical to the case of Figs. 6 to 8 and hence cor-

responding reference characters have been used for all other parts. The cigarettes are free to roll between these compartments when the cover is closed, but again, when the cover is opened, the communicating passage between the compartments of the case is restricted in area.

The last representative embodiment of the invention, shown in Figs. 10 and 11 of the drawings, illustrates a compact type of case having a greater depth than any type previously described, it being preferably dimensioned so as to be capable of holding a full package of twenty cigarettes. In this case, having a bottom 66 and sides 67, which are also provided with ribs or tongues 68, both the ends 69 are of equal height. A cover 70, having grooves to engage the tongues 68 of the sides, is thus slidably mounted on the case and a stop 71 limits opening movement of the cover. The dispensing means consist of a barrier 72 similar to that used in the types of cases illustrated in Figs. 1 to 5, and a rib or rake 73 which projects inwardly of the cover a distance sufficient to permit the rake to remove all cigarettes from the dispensing section except a cigarette 74 positioned in the dispensing pocket or trough of the case, and sufficient to close off, in cooperation with the barrier 72, the dispensing section from the main body of the case. Since the length of this case is less than the width thereof, no means need be provided to maintain cigarettes in substantial parallelism to the dispensing section, and the manner of operation of the case is identical to any of the other cases as previously described.

As has been mentioned before in this specification, some conception of the flexibility of the invention and the manner in which it can be accommodated to various types and styles of cases can be obtained from the cases represented and described herein. However, countless other modifications can be made utilizing the dispensing action of the invention, together with the means for maintaining alignment of the cigarettes, in instances where the design and dimensioning of the case makes the inclusion of this latter means advisable as can be determined from the outline and examples of satisfactory practice of the invention contained herein.

This application is a continuation in part of our co-pending application, Serial No. 611,970,

filed August 22, 1945, and entitled "Cigarette Dispensing Container," which has become abandoned.

We claim:

5 In a cigarette container constructed to hold a plurality of cigarettes in superimposed layers and having a cover mounted thereon for sliding movement from a closed to an open position, a dispensing section adjacent one end of said container and means to limit sliding movement of said cover to an amount sufficient to expose said dispensing section, means for preventing any cigarette within said container from attaining a position substantially perpendicular to the dispensing section thereof comprising a stationary rib, extending transversely of said container and disposed substantially parallel to said dispensing section and spaced therefrom a distance substantially less than the normal length of a cigarette, and a movable rib fixedly carried by said cover and extending parallel to said stationary rib, said movable rib being in vertical alignment with and separated from said stationary rib when said cover is in closed position by a vertical distance less than the normal diameter of a cigarette, a passage formed between said ribs upon sliding movement of said cover to its open position, the width of said passage being greater than the normal diameter of a cigarette.
